UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS.

DUMP-DOOR-OPERATING MECHANISM AND THE LIKE.

Application filed August 10, 1925. Serial No. 49,205.

My invention relates to dump door operating mechanisms and the like.

It is an object of my invention to provide novel means for rotating and operating 5 dump door operating shafts in a safe and convenient manner from a location remote from the shaft.

Another object of my invention is to provide in a shaft adapted to be reciprocated by 10 rotation thereof means whereby the exertion of turning force thereon will also operate to normally urge the reciprocatory movement of the shaft.

Another and more specific object of my 15 invention is to impart a movement of rotation to a shaft through the medium of a reciprocatory element adapted to be actuated through means of an oscillatable member.

My invention also resides in certain other 20 features and details of construction as will be hereinafter pointed out and claimed.

In the drawings forming a part of this specification, Figure 1 is a side elevational view of a portion of a car showing so much 25 of the car and door mechanism as embodies my improvements. Figure 2 is a transverse, sectional view taken through a portion of the car at the door mechanism and taken on a line corresponding substantially to a line 30 2—2 of Fig. 1. Figure 3 is a transverse sectional view, taken through the car and on a line corresponding substantially to a line 3—3 of Figure 1. Figure 4 is a perspective view of that portion of the framework adjacent the door operating mechanism. Figure 5 is a perspective view of the reciprocating element. Figure 6 is a view similar 35 to Figure 3 but showing the shaft actuating means in a different operating relation to the shaft. Figure 7 is a view 40 of the shaft actuating mechanism as shown in operative engagement with the shaft at the time of the end of the door closing operation, with the shaft beneath the door. Figure 8 is a view with the shaft in the same 45 position as Figure 7 but illustrating the parts of the mechanism positioned to commence the release operation of the mechanism. Figure 9 is a vertical elevational view showing 50 a portion of the end of a car with my improved construction embodied therein; the construction herein shown being an alternate arrangement applicable to cars wherein the door operating shafts are extended beyond the end sills of the car. Figure 10 is a side

longitudinal elevational view of the car showing so much of the car as will illustrate the parts shown in Fig. 9 in side view.

In said drawings and referring first to the construction illustrated in Figs. 1 to 8 60 inclusive, the invention is shown as applied to a gondola type of car provided with a longitudinal side sill 10 and transverse beam or bolster 11 secured thereto. One of the dump doors 12, of which the outer portion 65 only thereof is shown in dotted lines, is indicated in Fig. 2 and includes a suitable framework 13 to which are secured brackets 14 each provided with a serrated face 15. Connection is made between each door and a longitudinally extending shaft 16 by means 70 of flexible elements 17 shown conventionally in Fig. 2, of which there are preferably two associated with each door. On each shaft opposite each bracket 14 and co-operable 75 with the serrated faces 15 are serrated wheels 18 rigidly secured to the shaft 16.

The door shaft 16 is supported in bearing plates 19 secured to the transverse beams 11. Each of the bearing plates, as shown, is 80 formed with an elongated slot 20, having a depressed bearing portion 21 at the outer end thereof.

While the drawings show only a portion of 85 the car, it will be understood that the type of car referred to includes a longitudinal center sill construction, having the crossbeams 11 extending outwardly from the center sills to the side sills of the car and connected thereto, and the doors 12 are preferably 90 hinged to the center sill and disposed between the respective crossbearers.

In the particular construction illustrated in Figs. 1 to 8 inclusive, the mechanism associated with the shaft 16 consists of devices 95 for securing the shaft against unintentional reverse rotation thereof, during the raising operation, and for positively locking the shaft in supporting position beneath the doors, and is designated broadly by the reference character A. There is also a separate mechanism for inducing rotary movement of the shaft, said mechanism being designated broadly by the reference character B. In 100 this general type of mechanism, as the shaft 16 is turned in a closing direction, the flexible elements 17 wind on the shaft thus lifting the doors until the latter are almost in closed position, at which time further winding 105 of the members 17 on the shaft pull the 110

same inwardly along the bearing slots until the serrated wheels 18 engage with the rounded serrated faces 15 of the brackets and thereafter the shaft is moved under the doors, thus forcing the latter to fully closed position and also holding them closed with the load transferred to the shafts.

The mechanism A consists of a creeper formed of a plurality of plate sections 22-22 mounted on the shaft and movable in unison therewith, said creeper having an arm 23 outstanding therefrom, formed by bringing the respective plate sections 22-22 together and uniting the same by a rivet 24, a weight 15 pawl 25 pivotally mounted on the creeper and adapted to have co-operating engagement with a ratchet wheel 26 rigidly secured to the shaft, and a cam 27 which is pivotally mounted on the creeper and adapted to lock 20 the pawl 25 relatively to the ratchet wheel 26.

The arm 23 of the creeper is adapted to slide within a perforation 28 formed in a bracket guide 29. Said bracket guide 29 extends outwardly from the cross member 11 and is further braced laterally by a gusset member 30 extending outwardly from the outstanding flange 31 of the cross member 11.

The mechanism B for imparting rotary motion to the shaft consists of a reciprocating element 32 having a pair of spaced pawls 33-33 pivotally mounted thereon and co-operable with a ratchet wheel 34 which is rigidly mounted on the shaft. Said reciprocating element is preferably disposed beneath the shaft in alinement with the ratchet 34 and supported on the opposite sides of the shaft, one of said supports includes a lever 35 which is pivotally mounted at 36 on a fulcrum bracket 37 carried by the side sill 10 of the car, and the other support preferably consists of a fixed bracket on the framework of the car on which the said element is adapted to slide, and in the present embodiment of my invention the fixed guide 39 which forms the guide for the member A 29 is formed with an additional perforation 38 through which one end of the said element 32 is extended. Said reciprocating element 32 is preferably formed of two bar sections 39-39 united by rivets 40-40 and having a portion thereof intermediate said rivets separated to form a space 41 between said sections. The outer end of the element 32 is deflected downwardly at 42 and the end thereof is disposed between spaced walls 43-43 formed integrally with the lever member 35, and a pivot 44 operatively connects the said members. The lever member 35 is provided below the pivot 44 with a socket portion 45 adapted to receive a removable actuating tool whereby operation of the mechanism may be effected.

The fulcrum bracket 37 is provided with angularly related walls indicated at 46 and 47 and which are secured to the web and

flange of the channel side sill member 10 by rivets as indicated at 46 and 47 respectively, and a plurality of walls 48-48 depend from said angularly related walls, said walls 48-48 are spaced from each other sufficiently to receive pivotal end of the lever member 35.

The teeth 49 of the ratchet wheel 34 are somewhat undercut as indicated at 50, and the engaging portion 51 of each pawl 33 is shaped for efficient engagement between the parts to prevent accidental disengagement thereof. Each pawl 33 is provided at each side of the ratchet wheel 34 with webs 52-52.

In operation, assuming the doors to be opened, the outermost pawl member 33 is brought into engagement with the ratchet wheel 34 as indicated in Fig. 3 and the lever member 35 oscillated in an anti-clockwise direction by means of a removable bar 53, thereby moving reciprocating element 32 and therefore the pawl member 33 upwardly and away from the side of the car until the parts assume the position illustrated in Fig. 6, 90 the pawl 33 exerting a wedging action during such movement between the element 32 and the engaged tooth 49 of the cooperating ratchet wheel 34. The operation is repeated until such time as the flexible element is wound upon the shaft and the doors are lifted to a fully closed position and the shaft has travelled inwardly to a supporting position beneath the door, being drawn inwardly thereunder by reason of the flexible element 100 winding on the shaft, the parts then assuming the position as illustrated in Fig. 7.

The commencement of the door opening operation is illustrated in Fig. 8, the innermost pawl 33 being illustrated in engagement with the ratchet wheel 34 while the companion pawl used in the raising operation hangs in idle position. The length of the pawls and the extent of reciprocation of the element 32 are adjusted to enable operating engagement between the respective pawls and ratchet wheel throughout the entire movement of the shaft. The pawls 33 are adapted to be manually positioned into engagement with the ratchet wheel 34 on 115 each reciprocation of the element 32 thereby assuring complete safety to the operator as the pawls drop of their own weight to a vertically depending position below the ratchet wheel and therefore as the shaft 120 travels outwardly during the releasing operation of the doors, the shaft travels away from and independently of the reciprocating element 32 and co-operating pawls 33.

In Figs. 9 and 10 the invention is shown 125 as applied to a car wherein the mechanism is located outwardly of the end sill, the shaft being extended through the end sill of the car. In Figures 9 and 10, 110 indicates the end wall of the car, 111 the end sill, 112 130

the side sill of the car and 113 a horizontal gusset connecting the end sill and side sill. Mounted on the end sill is a slotted bracket 114, said bracket being formed with angular 5 walls 115 and 116 respectively secured to the side sill 112 of the car and to the horizontal gussets 113, said bracket also being provided with a plurality of depending walls 117-117 disposed in spaced relation and 10 braced to the main body of the bracket by horizontal flange 118 and vertical flanges 119 and 120. A bodily movable door operating shaft 121 is extended through the slot in the bracket 114, and a ratchet wheel 122 is 15 fixedly mounted on the end thereof. A creeper 123 is mounted on the shaft and formed with walls 124-124 disposed on either side of the ratchet wheel 122. A locking pawl 125 and co-operating locking 20 cam 126 are pivotally mounted between said walls 124-124, said members 125 and 126 being disposed above the ratchet wheel. The outer end of the creeper is extended within a perforation 127 formed in a bracket guide 25 128 carried by the end sill of the car. Pivotally mounted between the depending walls 117-117 of the bracket 114 is a lever member 129 formed with a socket portion 130, said lever is pivotally connected with a reciprocating element 131 at 132. The said element 131 is supported at its opposite end and adapted to have sliding movement in a perforation 133 formed in said guide 128. Oppositely disposed pawls 134, mounted on 30 the reciprocating element 131 are adapted to have co-operating engagement with the ratchet wheel 122 to rotate the shaft.

I have herein shown and described what I now consider the preferred manner of carrying out my invention, but the same is merely illustrative and I contemplate all changes and modifications that come within the scope of the claims appended hereto.

I claim:

45 1. In a dump car door operating mechanism, the combination with a rotatable shaft; of a lever pivotally mounted on the car structure to one side of the shaft; a guide on the opposite side of the shaft; a reciprocating element supported by said lever and

50 guide, and co-operating means between the reciprocating element and the shaft to effect rotation of the shaft by movement of the lever.

55 2. In a car door operating mechanism, the combination with an operating shaft adapted to be reciprocated by rotation thereof said shaft having a ratchet wheel thereon; of a movable member independent of the

60 shaft; a plurality of pawls disposed in substantially the same vertical plane, said pawls being oppositely disposed and mounted on independent pivots, one of said pawls being engageable with the ratchet wheel to rotate the shaft in one direction and the other pawl

being engageable to rotate the shaft in the opposite direction; and means for imparting motion to the movable member.

3. In a dump car, the combination with a door operating shaft adapted to be reciprocated by rotation thereof; of a member rigid with the shaft; a movable member disposed below the shaft; supporting means for the movable member disposed on the opposite sides of the shaft, one of said supporting means providing a link connection between the car structure and the movable member; and a co-operating member between the movable member and the rigid member on the shaft whereby movement of the movable member will induce a rotary movement of the shaft.

4. In a dump car, the combination with a door operating shaft adapted to be reciprocated by rotation thereof; of a member rigid with the shaft; a bracket guide secured to the car structure; a movable member adapted to have sliding motion within said guide; an oscillating member fulcrumed on the car and pivotally connected with the movable member; and a co-operating member between the movable member and the rigid member on the shaft whereby movement of the movable member will induce a rotary movement of the shaft.

5. In a railway car, the combination with a bodily movable shaft; of a toothed member fixedly mounted upon said shaft; an oscillatable member fulcrumed on the car structure independently of the shaft, said oscillatable member having an actuating tool receiving socket; a carriage member pivotally mounted on said oscillatable member intermediate its fulcrum and the socket portion; and a pawl carried by the carriage member, 105 said pawl being engageable with the ratchet wheel to rotate the shaft.

6. In a dump car door operating mechanism, the combination with a bodily movable shaft; of a reciprocating beam member 110 movable in a direction substantially at right angles to the shaft; carrying means for the beam member including a stationary guide and an oscillatable member; a pawl carried by said beam member and adapted to engage 115 the shaft to rotate the same.

7. In a car door operating mechanism including a bodily movable and rotatable shaft, a movable carriage member adapted to move in the direction of the shaft; a pawl carried by said carriage member; and oscillatable means for inducing a vertical and horizontal movement of the carriage member.

8. In a door operating mechanism, the combination with a rotatable operating shaft; of a ratchet wheel on the shaft; a stationary abutment disposed on one side of the shaft and an oscillatable member on the opposite side of said shaft; a beam member supported by said stationary abutment and os- 125 130

oscillatable member; and a pawl pivotally mounted on the beam member, said pawl being engageable with the ratchet wheel to rotate the shaft.

5 9. In a door operating mechanism, the combination with a rotatable operating shaft; of a ratchet wheel on the shaft; an oscillatable lever pivotally mounted on the car structure at one side of the operating 10 shaft; a beam member having one end thereof pivotally mounted on said oscillatable member and having the opposite end thereof supported by a fixed part of the car structure; and pawl mechanism carried by the 15 said beam, said pawl mechanism being engageable with the ratchet wheel on the shaft to rotate the same.

10. In a dump car, in combination; a discharge door; a rotatable and bodily movable shaft adapted to move from a position adjacent the free edge of the door to a position under the same; a slotted bearing having a depressed portion at one end constituting a bearing for the shaft; a flexible connection between the shaft and door, the said shaft being adapted to rotate in the depressed portion of the bearing and wind the flexible connection on the shaft, thereby raising the door and thereafter move bodily 20 to a supporting position under the door; means for imparting a movement of rotation to the shaft, said means including a reciprocating element and a pawl pivotally mounted on said reciprocating element adapted to 25 co-operate with the shaft to rotate the same; and means for actuating said reciprocating element, said actuating means being adapted to impart an upward movement to the reciprocating element during the winding operation 30 of the shaft.

11. In an operating mechanism for a pivoted dumping door of a vehicle having a framework, the combination with a shaft mounted in said framework and adapted for 45 rotation and bodily movement and arranged to move to a position beneath the free end of the door to support the latter in closed position; of a flexible connection between the door and shaft by means of which the door 50 is elevated and said shaft is rotated in one direction; means co-operable with said shaft to prevent accidental rotation of the latter in an unwinding direction when the door is being moved to closed position, said means 55 including an element formed with a projecting arm; a fixed guide on the framework adapted to support the said projecting arm; and means for effecting rotation of said shaft in either direction, said means including 60 a reciprocating element, operating devices on said reciprocating element and shaft,

said reciprocating element being pivotally supported at one end by a link device and at the opposite end by the said fixed guide on the framework.

65

12. In a dump car door operating mechanism, the combination with a rotatable shaft; of a ratchet wheel on the shaft; an element extending beneath the shaft and adapted to have a movement of reciprocation in a direction at right angles to the longitudinal axis of the shaft, said element being also adapted to have a turning movement during its movement of reciprocation and co-operating means between said element and shaft to effect rotation of the said shaft by movement of the said element.

70

13. In a dump car, the combination with a dumping door; of a rotary shaft for operating the door; and means for effecting rotation of the shaft, including a member slideable on the car structure in one direction and movable toward and away from said shaft in another direction, and an operating element for said member, said member and shaft having inter-engaging, intermediate drive means thereon.

80

14. In a dump car, the combination with a movable dumping door; of means for operating said door, including a rotary shaft and intermediate drive means, said shaft being operatively connected to the door and said intermediate drive means being operatively supported independently of the shaft for sliding movement in one direction and for movement toward the shaft in another direction.

85

15. In a railway car, the combination with a pivoted dump door; of a rotary operating shaft for said door; a member slidably and oscillatably supported on said car structure; inter-engaging means on said member and shaft for effecting rotation of the latter; and an operating lever swingingly supported on the car structure and permanently connected in operative relation to said member.

90

16. In a dump car, the combination with a dumping door; of a rotary shaft for operating the door, said shaft being mounted for bodily movement; and means for effecting rotation and bodily movement of said shaft including a member bodily movable on the car structure in one direction and movable in another direction toward and away from said shaft, and an operating element for said member.

95

In witness that I claim the foregoing I have hereunto subscribed my name this 6th day of August 1925.

ARGYLE CAMPBELL.
